UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,275,870.

Specification of Letters Patent.

Patented Aug. 13, 1918.

Application filed May 27, 1913. Serial No. 770,111.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 This invention relates to a new and improved means for automatically controlling the state of one or more computing heads as to adding, subtracting, etc., and is shown in connection with a machine of the combined 15 typewriting and computing type, such as that illustrated in an application of Walter Wright, No. 485,046, filed March 22, 1909, now Patent No. 1,244,397.

In prior automatic mechanisms for controlling the character of computation carried on by the computing heads, either the typewriter carriage or the computing mechanism has been burdened with this additional mechanism, which added to the complexity of the mechanism and slowed up the action thereof.

It is, therefore, an object of this invention to relieve the typewriter carriage and the computing mechanism of such extra burden by providing a separate device entirely distinct from the typewriter carriage and the computing mechanism, for automatically controlling the character of action of the computing heads.

30 In carrying out this object, use is made of the tabulating mechanism of the typewriter, so that every time a tabulating key is actuated to bring the typewriter carriage to a new computing zone or column, a controller, shown in the form of a disk, will be given a step movement to bring into play one or more positioning buttons according to the number of computing heads. These buttons are set to shift coöperating linkages 45 greater or less amounts according to their previous positions and according to the computing states desired. The linkages shift gearing to change the drive as to its direction or activity for both the master wheel 50 shaft and the assisting tens-carrying shaft of the corresponding computing heads.

The controller disk is provided with a power of its own and with an escapement therefor actuated by a bar universal to the tabulating keys, so that when any tabulat-

ing key is actuated, the disk will be driven a step by its own power to bring into play a new set of position-determining buttons. The controller disk may be returned manually at the end of each line of writing, so as to reenergize its motive means and so as to bring it back to its initial starting point.

In order to obviate the possibility of the operative forgetting to reenergize the controller motive means and to return the controller disk to its starting point, a lock may be provided, which, at the end of a written line, will come into play to prevent the actuation of the controller and also to prevent the actuation of the tabulating keys. This lock may be adjusted to any of a plurality of positions corresponding to the terminal of the extent of controlling action desired.

In case of an error, or for any other reason, the automatic mechanism may be operatively disconnected and the state of the computing heads controlled manually. For this purpose, the shifter operated upon by the positioning buttons is made composite, so that the train of connection between the controller and the computing heads can be interrupted at this point and the state of the computing heads determined by the shifting of manual levers.

Other features and advantages will hereinafter appear.

Figure 1 is a view partly in elevation and partly in section taken from front to rear of the machine, showing the combined type-writing and computing machine as a whole, with parts omitted for the sake of simplifying the showing.

Fig. 2 is a skeleton perspective view showing the connection of one of the numeral keys to the valuating mechanism.

Fig. 3 is a top plan view of the tabulating rack showing four tabulating stops thereon.

Fig. 4 is a skeleton perspective view showing the relation of the tabulating keys to the automatic controller and the connection of the automatic controller to the state-controlling levers for each computing head.

Fig. 5 is a detail section taken from front to rear through one of the computing heads.

Fig. 6 is a bottom plan view looking at the controller disk from beneath, with part of the disk broken away to show the relation of the top shifter to one of the position-determining buttons on the disk.

Fig. 7 is a fragmentary view in front elevation.

Fig. 8 is a diagrammatic horizontal plan view looking from the bottom up, with the controller disk removed for the sake of simplicity.

Fig. 9 is an enlarged detail view of the controller disk separated from the other parts.

10 Fig. 10 is a vertical section taken from right to left through the state-controlling mechanism.

15 Fig. 11 is a detail perspective view showing the action of the lock or guard in preventing a further action of the escapement for the controller.

20 Referring more particularly to the separate parts of this invention as embodied in the form shown in the drawings, 1 indicates numeral keys and 2 character keys which are mounted on key-levers 3, so as to depress the same and thus rock bell cranks 4 to swing type-bars 5 up rearwardly against the front side of a platen 6 mounted on a traveling carriage 7. The carriage 7 has a traveling movement under the control of an escapement indicated in general at 8, which includes a rack bar 9 pivotally mounted, by means of arms 10, on the carriage 7, and 25 engaging a pinion 11 fixed to an escapement wheel 12. The escapement wheel 12 is controlled in its movement by fixed and movable dogs 13, which in turn are actuated when any one of the type keys is actuated, 30 by means of a universal frame 14, which is engaged by a heel 15 on each of the type-bars 5 as the latter swing upwardly to strike the platen 6.

35 In addition to this step-by-step movement, 40 the carriage 7 may be given a jump or tabulating movement. For this purpose, there are provided tabulating keys 16, mounted on key-levers 17, which are pivoted intermediate their ends, and support at 45 their rear ends plunger stops 18. When a tabulating key 16 is depressed, it raises the associated plunger stop 18 to bring the same into the path of a tabulating stop 19 adjustably mounted on a rack 20 carried by the 50 carriage 7.

55 When any one of the plunger stops 18 is raised, it must release the carriage 7 from its escapement mechanism, indicated at 8. For this purpose, there is provided a lever 21 universal to all of the plunger stops 18 and engaging shoulders 22 provided thereon. This lever 21 when rocked, will draw on a link 23 to rock a lever 24 carrying at its forward end a roller 25 engaging under 60 the rack 9, so that when any one of the tabulating keys 16 is actuated, it will raise the rack 9 out of engagement with the pinion 11, permitting the carriage 7 to travel under the traction of a spring barrel indicated 65 at 26.

When any one of the numeral keys 1 is actuated, in addition to printing the number by means of the type-bars 5 swinging up to strike the work-sheet on the carriage 7, it also, as will be seen by reference to Fig. 2, pulls on a hook 27 to rock a bell crank 28, the latter drawing on a link 29 to rock a lever 30. The lever 30 carries at one end, a plunger 31 arranged in apposition to one of a series of index pins 32 suitably mounted on an index or valuating wheel 33. Thus when a numeral key 1 is actuated, by virtue of the connected linkage, it will force the associated plunger 31 against the apposite pin 32, setting it from a projecting position on one side of the valuating wheel 33 to a projecting position on the far side of the valuating wheel 33. There is one of these linkages and plungers for each of the numeral keys 1, and they are each arranged in apposition to one of the pins 32.

75 The plungers 31 are located in apposition to the pins 32 distant amounts corresponding to their particular numeral keys; from a four-tooth detent wheel 34. This detent wheel 34 normally engages one of the pins 32 which has been previously set up to its position projecting on the far side of the wheel 33. The detent wheel 34 locks the 80 valuating wheel 33 against rotation by engagement with this pin, and is in turn locked by an escapement wheel 35 connected thereto by a shaft 36. This escapement wheel 35 normally engages one of a pair of detent 85 dogs 37 and 38 provided on a rock shaft 39.

90 When a numeral key is actuated, this shaft 39 is first rotated in one direction to permit a movement of one of the teeth of the escapement wheel 35 from engagement 95 with one of the dogs, 37, to engagement with the other of the dogs, 38. Then when the numeral key is returned to its normal raised position, the shaft 39 is rocked in the opposite direction to permit the tooth in engagement with the dog 38 to slip by and the next tooth on the detent 35 will then come into engagement with the first dog, 37, permitting a quarter rotation of the detent wheel 34. This is all caused by the tendency of 100 the valuating wheel 33 to rotate, as will be hereinafter described, which rotation tends to return the detent wheel 34 by reason of the fact that the set pin on the valuating wheel 33 tends to escape by the detent 105 wheel 34.

110 To rock the shaft 39 at the actuation of any of the numeral keys 1, all of the links 29 extend through slots 40 in a collar plate 41, which is mounted for sliding movement 115 against the tension of a spring 42. When one of the links 29 is drawn on by the actuation of its associated numeral key 1, then the tail end of the corresponding lever 30 will engage the collar plate 41, to force the 120 125 130

same rearwardly against the tension of the spring 42. The collar plate 41 coöperates with a second collar plate 43 spaced therefrom to rock a lever 44 resting therebetween, 5 at one end. The opposite end of the lever 44 is connected by a link 45, to an arm 46 on the rock shaft 39.

Thus it will be seen that when a numeral key 1 is depressed to set a pin 32 through the 10 aid of the plunger 31, then the shaft 39 will be rocked in one direction, and when the numeral key 1 is returned, the shaft will be rocked in the opposite direction permitting a quarter of a revolution of the detent wheel 15 34, so that the pin in engagement therewith will escape by the same and a newly set pin will come into engagement therewith and enable the relocking of the valuating wheel 33. The extent of movement of the 20 valuating wheel 33 depends upon the particular numeral key actuated. That is to say, if the "2" key were actuated, the valuating wheel would move a distance corresponding to the distance of the second pin 25 removed from the pin engaging the locking detent wheel 34.

The valuating wheel 33 may be normally under a tendency to rotate in any suitable manner, as by being provided with a shaft 30 47, having a gear 48 meshing with a gear 49 on a shaft 50. The shaft 50 may also be provided with a bevel gear 51 (Fig. 1) engaged by a bevel gear 52 on a shaft 53, which in turn may be driven from a motor 35 54 through the intermediary of meshing bevel gears 55 and 56 mounted, respectively, on the motor shaft and the shaft 53. A slip clutch may be provided in this gearing, so that when the valuating wheel 33 is locked 40 against movement, the motor may continue to rotate without damage to the mechanism.

The purpose of this rotation of the valuating wheel 33 is to enable the running-up 45 of numbers digit by digit into the computing wheels of one or more computing heads, of which two are shown at 57 and 58. For this purpose, when the valuating wheel 33 is permitted to rotate and the bevel gear 51 is likewise rotated, this movement will be 50 communicated, by means of a bevel gear 59 meshing with the bevel gear 51, to a shaft 60, which in turn transmits it through a pair of intermeshing bevel gears 61 and 62, to a vertical shaft 63. This latter shaft is arranged 55 to drive the master-wheel shafts, of which one is indicated at 64 in Fig. 5. Therefore, each master-wheel shaft is provided at its outer end with a bevel gear, indicated respectively in connection with the 60 computing heads 57 and 58, at 65 and 66.

Meshing with the bevel gear 65, there is provided a pair of bevel gears 67 and 68 loosely mounted on the shaft 63. Likewise meshing with the bevel gear 66, there is provided 65 a pair of loosely-mounted bevel gears

69 and 70 loose on the shaft 63. Between the pairs of bevel gears 67, 68 and 69, 70, there are provided shiftable clutches 71 and 72, which are capable of occupying any one of three positions corresponding to the rotation of the gears 65 and 66 in one direction or the other, or to a non-rotation of these gears. That is to say, each of the clutches 71 and 72 is provided on its top and bottom with teeth arranged to engage corresponding teeth on the inwardly-facing sides of the paired bevel gears. 70 75

It will thus be seen that when one of the clutches 71 or 72 occupies a position connecting one of the paired bevel gears to the shaft 80 63, the associated master-wheel shaft 64 will be driven in one direction, and when in a position connecting the other paired bevel gear to the shaft 63, the master-wheel shaft 85 64 will be driven in the opposite direction. It will be further seen that when the clutch occupies an intermediate position in which neither of the paired bevel gears is connected to the shaft 63, then the associated master-wheel shaft 64 will remain dormant 90 or silent. The master-wheel shaft 64 in each case is provided with a master-wheel indicated at 73, which engages internally-formed teeth 74 on a computing wheel 75. This computing wheel 75 is also provided 95 with external teeth 76 meshing with a gear 77 carried by a dial wheel 78, which is adapted to exhibit the numbers shown up thereon through a sight opening 79 in a computing head casing 80. 100

The master wheel 73 may be moved step by step through the several computing wheels of both the computing heads to correspond to the writing of the different digits on the work-sheet located on the typewriter carriage, by means of a lever 191, which may be intermittently connected to the carriage through the intermediary of a latch 192, which engages the different tappets or stops 19 carried by the carriage in a manner 110 shown and described in an application of Walter Wright, No. 574,813, filed August 1, 1910, now Patent 1,244,398.

When one of the dial wheels and its associated computing wheel has made a complete revolution, that is, when the number exhibited passes from "9" to "0," it is necessary to carry one to the computing wheel of next higher denomination. For this purpose, there is provided a tens-carrying mechanism, indicated in general at 81, which depends for its action on the rotation and direction of rotation of a rubber roller 82, which is driven from a shaft 83 by interconnecting gearing indicated in general at 115 84. There is a shaft 83 for each of the computing heads, and it is provided, in this case, on its outer end with a bevel gear, indicated, in the case of the computing heads 57 and 58, at 85 and 86. The bevel gears 120 125 130

85 and 86 similar to the bevel gears for the master-wheel shafts, mesh with paired bevel gears loosely mounted on a shaft 87. These bevel gears are indicated, in the case of the 5 gear 85, by the numerals 88 and 89, and in the case of the bevel gear 86, by the numerals 90 and 91. Clutches 92 and 93 are provided between the pairs of gears to connect one or the other of the paired gears in 10 driving relation with the shaft 87. The shaft 87 is also driven from the motor 54 through the intermediary of a shaft 94, connected by a pair of bevel gears 95 and 96 at one end to the shaft 87, and by a pair of 15 bevel gears 97 and 98 to the shaft 63 at the other end.

To shift the clutches for the master-wheel shaft and the tens-carrying shaft of each computing head, there is provided a composite shifting lever, indicated in the case of the computing head 57, at 99, and in the case of the computing head 58, at 100. These shifting levers are identical and only one will be described. The composite shifting 20 lever consists of a main lever 101, pivoted at 102, and provided with a pin 103 engaging in a groove in the master-wheel clutch 71 or 72. Pivotedly mounted on a pin 104 provided on the main lever 101, there is provided 25 a supplementary lever 105, which has a movement relative to the main lever 101, limited by a pair of fingers 106 and 107 engaging opposite sides of the pivot 102. This supplementary lever 105 is provided with a 30 pin 108, which engages in a circumferential groove provided in one of the tens-carrying clutches 92 or 93. The lost motion between the main lever 101 and the supplementary lever 105 is provided, so as to permit the 35 settling of the teeth in the different clutch faces. This lost motion is taken up by a spring 109.

It will thus be seen that when one of the composite levers is shifted, the associated 40 clutches will be shifted to concomitantly change the drive of the master-wheel shaft and the assisting tens-carrying shaft, so that they will always rotate in corresponding directions either to add or subtract, or they 45 will not rotate at all in the case where it is desired to have the associated computing heads silent.

Of course, these composite levers might be shifted directly manually. In this case, 50 however, each of the main levers is provided with an eye 110, with which engage links 111 and 112 for the computing heads 57 and 58, respectively. The links 111 and 112 are connected, respectively, (Fig. 4) to separate bell 55 cranks 113 and 114, pivotally mounted on a stub shaft 115, so that they may be rocked by these bell cranks. The bell cranks are in turn rocked by links 116 and 117, which are drawn on by levers 118 and 119, to which 60 they are connected. These levers are pro-

vided with hand-grips 120 and 121, to enable them to be manually manipulated, if desired, one of the hand-grips being bent over to permit more ready access to the other hand-grip.

The levers 118 and 119 are pivotally mounted intermediate their ends on a stub shaft 122, so that they may be rocked by a pair of links 123 and 124, which are connected thereto at their lower ends. The links 70 123 and 124 may in turn be drawn on by composite shifters 125 and 126, separately pivoted on a stub shaft 127. Each of the composite shifters is provided with a centralizing element 128 and 129, respectively, 75 which in the case of the latter faces upwardly, and in the case of the former faces downwardly, to engage position-determining buttons 130 provided on opposite sides of a rotatable controller disk 131. Each centralizing element 128 and 129 may be formed by providing a pair of flanges 132 and 133 spaced apart from each other and provided with parallel reaches 134 and 135 (Fig. 8), to 80 form a channel therebetween, in which one 85 of the position-determining buttons 130 can pass to fix the location of the shifter 125 for any particular position of the disk 131. The flanges 132 and 133 both flare outwardly from opposite sides of the parallel reaches 134 90 and 135, so as to form guideways forcing the shifter to move to such a position that the co-operating position-determining button 130 may enter the channel formed between the parallel reaches. The reason for flaring 95 the centralizing device in both directions is to permit the actuating movement of the disk 131 and a returning or ineffective movement of this disk.

The disk 131 forms a part of the controlling 100 mechanism and is arranged to be given a step-by-step movement at the actuation of each of the tabulating keys 16 to bring the typewriter carriage into a new computing zone or column. For this purpose, the controller 110 disk 131 is secured to an escapement wheel 136, which has secured thereto a gear 137 meshing with a rack 138 on a bar 139. The bar 139 is guided for movement on a plate 140 and has connected thereto a spring 141, 115 which is normally under a tension tending to drive the rack bar 139 and thus rotate the gear 137 with the escapement wheel 136 and the controller disk 131. This movement, however, is prevented by a dog 142 which 120 engages the teeth 149 of the escapement wheel 136. The dog 142 is mounted on a bar or rail 143, which is universal to all of the tabulating keys 16, with the possible exception of the millions key, indicated at 144.

The universal bar 143 is supported by a pair of spaced arms 145, which are mounted on a rock shaft 146, so as to form a universal frame. This frame is normally held in a raised position by one or more springs 147 130

coiled about the shaft 146 and engaging under the arms 145.

When the universal frame, including the universal bar 143, is in its normal raised position, the dog 142 will have the toe 148 thereof in engagement with one of the teeth 149 of the escapement wheel 136, preventing rotation thereof under the tension of the spring 141. As soon, however, as one of the 10 tabulating keys 16 is depressed, it will engage the universal bar 143 and depress the same against the tension of the springs 147, thereby moving the toe of the dog 142 out of engagement with the escapement wheel 15. 136. Before, however, this wheel can complete its movement, a second pawl or dog 150, which is somewhat shorter than the dog 142, will be depressed to bring the toe 151 thereof into the path of movement of 20 the next tooth 149 on the escapement wheel 136, locking the escapement wheel and the controller disk 131 from further rotation.

When the tabulating key just depressed returns to its normal position, the universal 25 bar 143 will likewise return, carrying both the dogs 142 and 150 with it, thereby removing the dog 150 from engagement with the tooth 149 on the escapement wheel 136, and bringing the dog 142 into engagement 30 with this tooth, so that during one up-and-down movement of a tabulating key, the dogs will alternate in action, permitting a single step movement of the escapement wheel 136 corresponding to the distance between two of the teeth 149, and thus permitting a single step movement of the controller disk 131.

The dogs 142 and 150 are connected to a sleeve 152, which is common to both of them, 40 and which is further pivoted on the bar 143, so as to admit of a swinging movement of the dogs relatively thereto. This swinging movement may be made use of in permitting a backward rotation of the escapement wheel 136, the teeth 149 thereof being inclined on 45 their rear surfaces to cam the dogs aside.

In order to permit this movement of the dogs and yet maintain them normally in co-operative relation with respect to the teeth 50 149, there is provided a spring 153, which is secured to a lug 154 on the bar 143 and extends through an opening 155 in one of the dogs, 142. Inasmuch as the dogs are secured together by the common sleeve 152, the 55 spring 153 will answer for both of them. The inward motion of the dogs under the urging of the spring 153 is limited by a stop 190.

After a single series of controlling 60 actions of this controlling mechanism has been effected, as, for example, when a complete line of numbers has been written on the typewriter, then it is necessary to retension the spring 141 and return the controller disk 131 to its normal position. For this pur-

pose, the bar 139 may be provided with a hand-hold 156 at one end thereof, so that the operative can grasp the same and return the bar 139 to its original starting position, and thus reenergize or retension the 70 spring 141 connected thereto. Inasmuch as the rack of the bar 139 still meshes with the gear 137, then this gear will be rotated in a counter-direction, that is, in the opposite direction to that shown by the arrows in 75 Fig. 4, so that the escapement wheel 136 and the controller disk 131 will be returned to their original starting positions.

While the controller disk 131 may be of any suitable form, the type adopted in this 80 instance consists in having a flat disk with a series of perforations therein arranged in a circle. Every other perforation may be used for the position-determining buttons 130 on one side of the disk, and the intermediate perforations may be used for the position-determining buttons on the opposite side of the disk. That is to say, with two computing heads, the alternate holes or perforations correspond to the controlling buttons on opposite sides of the disk and thus to the two shifters 125 and 126 and their accordant computing heads. 85 90

The position-determining buttons are shown in the form of screw-bolts, each provided with a head 157 (Figs. 9 and 10) and an eccentrically-located shank 158 of a size to conform to the holes or perforations in the disk 131. The shanks 158 are screw-threaded to enable the attachment thereto of 95 locking nuts 159, which secure the position-determining buttons in any adjusted position. The adjustment of the buttons and the locking of them in position may be aided by a screw-driver slot 160 provided in each 100 head 157.

The position-determining buttons 130 are to be located on the disk 131 in one of three positions corresponding to adding, neutral and subtracting. By reference to Fig. 9, 110 these three positions will be noted for the top side of the disk. 161 indicates a position-determining button in its adding adjustment, that is, with the head 157 thereof swung to its position farthest from the center of the disk 131; 162 indicates a position-determining button in its subtracting position with the head 157 swung to its position nearest the center of the disk 131; and 115 163 indicates the adjustment of the position-determining button to a location corresponding to a neutral condition of the computing head, that is to say, with the head 157 thereof located in a position midway between its extreme outer and inner possible locations. 120 Of course it is to be understood that the heads 157 of the position-determining buttons are considerably larger and deeper than the nuts 159 which hold them in position, so that the centralizing element 128 130

may engage the heads 157 of the buttons which are to control them, without engaging and without being disturbed by the nuts 159 of the positioning buttons whose heads 5 are located on the opposite side of the disk.

It may often be necessary to adjust the state of the computing heads manually independent of the automatic controlling mechanism, as in case it is desired to correct an 10 error. In such an event, the manual levers 118 and 119 may be manipulated in such a manner as to leave the automatic controlling mechanism in the same condition. For this purpose, the shifters 125 and 126 are 15 composite, that is to say, formed of two parts having a relative movement when necessary. In other words, each composite shifter includes a bell crank lever 164, to one arm 165 of which is secured the centralizing 20 element 128 or 129. The other arm 166 of the bell crank lever has a mate in an arm 167, which is pivoted to the same stub shaft 127 in close juxtaposition thereto. The arm 167 is normally connected to the arm 166, so 25 that the two will move together as a unit by a latch 168, which is held in its locking position by a spring 169. The arm 167 has a perforation 170 in which the link 123 or 124 is hooked to form the connection to the 30 corresponding lever 118 or 119.

The latch 168 is pivoted to an extension 171 on the arm 167, and is provided with a beveled locking tooth 172, which engages a corresponding socket 173 in the arm 166. 35 This yielding connection between the two parts of the shifting lever permits the forcible disengagement of the latch 168 and thus of the arm 167 from the arm 166 when the associated lever 118 or 119 is manipulated 40 to vary the state of the associated computing head from that determined by the particular positioning button 130 in engagement with the centralizing element 128 or 129. In other words, by this forcible disengagement, the 45 character of computation can be controlled manually independent of the automatic controlling means.

In addition to the fact that the latch 168 may be readily cammed out of its socket 50 while the bell crank lever 164 of the shifter is held stationary by engagement with one of the buttons 130, this latch may also be forced into position when the corresponding lever 118, 119, is returned to a position corresponding to the position of the bell crank 55 lever 164. For this purpose, the arm 166 of the lever 164, which is spread out at the point of engagement with the latch 168, is beveled at both sides of the notch 173, as at 60 174 and 175, to admit of the camming by of the latch on a re-mating relative movement of the arms 166 and 167. The limits of movement of the shifter may be determined by stops 176.

65 It might happen that the operative after

completing a line of writing and running through the line of computing zones, would forget to return the rack bar 139 at the same time that the typewriter carriage is returned to its starting position for a new line. A 70 lock is therefore provided to guard against such a mistake, and this lock is arranged to prevent the actuation of the tabulating keys 16, with the possible exception of the millions key 144, so that the carriage cannot be 75 properly positioned for the different computing zones, whereby the state-controlling mechanism must be re-set before the typewriting can be commenced. For this purpose, the escapement wheel 136 is provided 80 with a series of perforations 177 arranged at intervals corresponding to the step movements of the escapement wheel and of the controller disk 131, and preferably in register with the teeth 149 of the escapement 85 wheel 136. These perforations may be numbered from "0" to "10" to correspond to the initial position of the typewriter carriage and the several possible computing zones thereof. The alternate perforations for the 90 positioning-determining buttons on the controller disk 131 may be correspondingly numbered, so that the stopping points of this disk will accord with the different columns or zones as typewritten. A lock 178 may be 95 secured, by means of a bolt 179, at any one of these points by passing the bolt through one of these openings 177. The lock 178 projects beyond the root circle of the escapement wheel, and, in fact, conforms at its 100 outer end to the particular tooth with which it is brought into register, on one side thereof, that is, on the inclined or back side thereof. This lock, however, projects beyond the locking side of the tooth with which it is 105 operating, so as to prevent the dog 142 from being depressed out of the path of this particular tooth.

It will be seen that after the controller has been moved step by step to the end of 110 the desired controlling sphere thereof, then the dog 142 will be located directly above the guard or lock 178, preventing a further actuation of any of the tabulating keys 16. In this instance, the guard is shown as being 115 located at the fourth station corresponding to four computing zones or columns, beyond which the carriage cannot be tabulated and the computing mechanism controlled in its state until the automatic controlling mechanism has been returned to its initial position. 120

In preparing the machine for operation, the position-determining buttons 130 are properly located on the disk 131 for the sequence of computing actions desired of the 125 computing heads. In this instance, the top side of the disk 131 controls the upper computing head and the bottom side of the disk 131 controls the lower computing head, there being but two heads shown. If it is desired 130

- to add in any particular zone, the button will be located in the position illustrated in Fig. 9, at 161. If it is desired to have the computing head silent in any zone a button in a 5 position such as that indicated at 163, will be used. If, on the other hand, it is desired to subtract in any computing zone, the positioning button will be adjusted to a location shown at 162.
- 10 When the buttons for the successive stops or stopping points of the controlling mechanism have been properly adjusted, it may be determined how far the computing mechanism is desired to be used. That is to say, 15 if, as illustrated in the drawings, it is desired to have four computing zones or columns, there will be placed on the rack 20 of the carriage, four of the carriage stops 19, as illustrated in Fig. 3, so that the carriage 20 will be positioned by an actuation of the tabulating keys for four different columns or zones. The guard or lock 178 can then be positioned on the escapement wheel 136 at the number "4" position corresponding to the 25 termination of the fourth step movement of this controlling mechanism. That is to say, the "0" position corresponds to the initial position of the carriage; the "1" position corresponds to the first computing zone; the 30 "2" position to the second computing zone, and so on. The controlling mechanism is arranged with the spring 141 completely tensioned and the tooth 149 of the escapement wheel 136 in register with the "0" position in 35 engagement with the dog 142. The carriage is likewise positioned to its extreme location at the right. The tabulating key 16 is then struck to bring the carriage to the first computing zone or column. This actuation of 40 the tabulating key will not only determine the position of the carriage but will depress the universal bar 143 and bring the dog 142 out of engagement with the initial tooth 149 (at "0" zone), concomitantly bringing the 45 short dog 150 into the path of the next tooth.
- When the tabulating key returns, the springs 127 will likewise return the universal frame including the universal bar 143, so that the dog 150 is removed from engagement with the tooth on the escapement wheel 136, and this escapement wheel with the controller disk 131 flies around under the propulsion of the spring 141 until this 50 next tooth which has just escaped past the dog 150, comes into engagement with the dog 142 which by this time has risen into the path of this tooth.
- During this movement, the positioning buttons on the top and bottom of the controller disk 131 will engage the bottom and 55 top of the centralizing elements 128 and 129, and adjust them to positions corresponding to the positions of the heads of these buttons. This movement will be transmitted to 60 the clutch-shifting composite levers 99 and

100, so that the drive and character of drive of the master-wheel shafts and the tens-carrying shafts of the computing heads will be determined, and thus the state or character of computation carried on by these 70 computing heads determined.

After the digits of a number to be computed in this first computing zone or column have been written on the work-sheet on the carriage and run up in the computing heads, 75 then the tabulating mechanism will be again actuated to bring the carriage to the next computing zone or column, which actuation will likewise cause a step movement of the controller or controlling mechanism, to provide a re-adjustment of the states of the computing heads, if it should so happen that it is desired to change them for the next column. Of course, the positioning buttons in two successive columns might be the same 80 for any one computing head or for both computing heads, so that the mechanism would remain in its state of previous adjustment. This action is repeated for each computing zone or column until the fourth 85 computing zone or column in the example given, is finished. Then it will be impossible to actuate the tabulating mechanism as the dog 142 will engage the guard or lock 178 and be prohibited from any downward 90 movement. This, then, shows that the end of the sphere of control of the controlling mechanism has been reached for the particular adjustment thereof, and that it is necessary for the operative to return the controlling mechanism to its original position and retension the spring 147 by actuating the hand-hold 156. This, then, while admitting of the automatic control of the states 95 of a plurality of computing heads for the different zones of columns, prevents an overrunning of this mechanism, and further prevents states becoming discordant with the particular zones of the typewriter carriage with which the successive step movements 100 are intended to accord.

If it should be desired to manipulate the composite state-controlling levers for any computing head, so as to obtain a state other than determined by the automatic mechanism, as in case it is necessary to make a correction, then the particular lever 118, 119, corresponding to the computing head which it is desired to control, is manipulated, which may be done without a disruption of the mechanism or an interference with the automatic mechanism by virtue of the composite character of the shifters 125, 126.

In case it should be required to actuate 125 the typewriting mechanism to space the carriage without operating the state-controlling mechanism, the millions key could be used, inasmuch as it does not project above the universal bar 143.

It will thus be seen that there is provided an automatic controller or controlling mechanism for determining the state of a plurality of computing heads according to a predetermined plan, to correspond to the several computing zones or columns of the typewriter carriage, without burdening the typewriter carriage and without relying upon the computing mechanism itself. That is to say, there is provided a distinct and independent mechanism which varies the character of computation according to a predetermined plan.

Variations may be resorted to within the scope of the invention, and portions of the improvements may be used without others.

Having thus described my invention, I claim:

1. The combination with one or more computing heads, of a traveling carriage, computing mechanism for running up numbers in said computing heads, and power mechanism acting independently of the position of said carriage for varying the state of said computing heads to correspond with the computing action desired of the several numbers in the different zones or columns as determined by the position of said carriage.

2. The combination with one or more computing heads, of a traveling carriage, computing mechanism governed as to position by said carriage for running up numbers in said computing heads, and power mechanism acting independently of the position of said carriage and of said computing mechanism for controlling the state of said computing heads as to the character of computation carried on thereby, to correspond with the computation desired for the different numbers in the several computing zones or columns as determined by said carriage in its traveling movement.

3. The combination with one or more computing heads, of a traveling carriage, numeral keys, computing mechanism for running up numbers in said computing heads as determined by said keys, a source of power for said computing mechanism, an automatic mechanism for governing the state of said computing heads according to a predetermined sequence, and a source of power separate from said first-mentioned source of power for actuating said automatic mechanism.

4. The combination with one or more computing heads, of a traveling carriage, tabulating mechanism including tabulating keys for determining the position of said carriage, and automatic mechanism actuated by said tabulating keys for governing the state of said computing heads.

5. The combination with a traveling carriage, of motive means for traversing said carriage, one or more computing heads, com-

puting mechanism for running up numbers on said computing heads, motive means for said computing mechanism, automatic mechanism for governing the state of said computing heads according to a predetermined sequence, and motive means for said automatic mechanism separate from both said first-mentioned motive means.

6. The combination with a traveling carriage, of motive means for traversing said carriage, one or more computing heads, computing mechanism for running up numbers in said computing heads, automatic mechanism for governing the state of said computing heads according to a predetermined sequence, motive means for said automatic mechanism separate from said traversing means, tabulating mechanism for governing the position of said carriage, and means actuated by said tabulating mechanism for governing the drive of said automatic mechanism and said carriage traversing means.

7. The combination with a traveling carriage, of an escapement for said carriage, one or more computing heads, an automatic mechanism for controlling the state of said computing heads, an escapement for said automatic mechanism, and key means for controlling the action of both of said escapements concomitantly.

8. The combination with a typewriting mechanism including a traveling carriage and escapement mechanism therefor, of a computing mechanism, automatic mechanism for determining the state of said computing mechanism to accord with different typewriter columns as written by said typewriting mechanism, an escapement for said automatic mechanism, and key means for operating said escapement.

9. The combination with a plurality of computing heads, of a controlling mechanism for governing the state of said computing heads, said controlling mechanism including a rotatable disk, a series of position-determining members on said disk for controlling said plurality of heads, means for rotating said disk, an escapement for said disk, and means for actuating said escapement.

10. The combination with one or more computing heads, of automatic means for controlling all of said computing heads according to a predetermined plan, said automatic means including a single rotatable disk for all of said heads, a plurality of position-determining buttons on said disk, motive means for rotating said disk, an escapement normally preventing the rotation of said disk by said motive means, and means for releasing said escapement to admit of the movement of said disk under the propulsion of said motive means.

11. The combination with one or more computing heads, of an automatic control-

- ling mechanism for governing the state of said computing heads according to a predetermined plan, said automatic controlling mechanism including a rotatable disk, a plurality of positioning buttons on said disk, a gear connected to said disk, a rack meshing with said gear, a spring connected to said rack tending to rotate said gear and said disk, and means for controlling the rotation 5 of said disk under the propulsion of said spring.
12. The combination with a typewriting mechanism including a traveling carriage, of a computing mechanism, automatic mechanism for governing the state of said computing mechanism, tabulator keys for said carriage, means enabling said keys to control said governing mechanism, including a rotatable disk, means tending to rotate said 15 disk, and a step-by-step escapement operable by said tabulator keys enabling step-by-step movements of said disk.
13. The combination with a typewriting mechanism including a traveling carriage, 20 escapement mechanism and tabulator keys for said carriage, of a computing mechanism, and an automatic mechanism for controlling the state of said computing mechanism, said automatic mechanism including means operated by certain of said tabulator keys for enabling step-by-step movements of certain parts of said automatic mechanism.
14. The combination with a computing mechanism, of a typewriting mechanism including a traveling carriage and a plurality 25 of tabulator keys for controlling the action of said carriage, and an automatic mechanism for governing the state of said computing mechanism, said automatic mechanism including a rotatable disk, means normally tending to rotate said disk, and an escapement for said disk operable by certain of 30 said tabulator keys.
15. The combination with a computing mechanism, of a typewriting mechanism including a series of keys for controlling the action of parts of said typewriting mechanism, and an automatic mechanism for controlling the state of said computing mechanism, said automatic mechanism including a rotatable disk, means tending to rotate said 35 disk, an escapement wheel connecting to said disk, a bar universal to a certain group of said keys, and a pair of dogs carried by said bar to be brought alternately into engagement with said escapement wheel to control a step-by-step movement thereof and of said disk.
16. The combination with a typewriting mechanism including a traveling carriage and a series of tabulating keys for controlling the position of said carriage, of a computing mechanism, and automatic mechanism for determining the state of said computing mechanism, said automatic mecha- 40 nism including a controller disk, means normally tending to rotate said disk, an escapement wheel for said disk, a bar universal to a plurality of said tabulating keys, and a pair of dogs mounted on said bar to move therewith, so as to alternately engage said escapement wheel and enable a step-by-step movement of said disk.
17. The combination with a typewriting mechanism including a series of keys for actuating parts of said typewriting mechanism, of a computing mechanism, and an automatic mechanism for controlling the state of said computing mechanism, including a controller disk, means normally tending to rotate said disk, an escapement wheel for said disk, a bar universal to a plurality of said keys, a sleeve pivotally mounted on said bar, a pair of dogs secured to said sleeve, said dogs being of different effective magnitudes so as to alternately engage said escapement wheel, and a spring for normally holding said dogs for engagement with said wheel.
18. The combination with a typewriting mechanism including a series of keys for actuating parts of said typewriting mechanism, a computing mechanism, and automatic mechanism for controlling the state of said computing mechanism, said automatic mechanism including a controller disk, means normally tending to rotate said disk, an escapement wheel for said disk, a bar universal to a plurality of said keys, a sleeve pivotally mounted on said bar, a pair of dogs secured to said sleeve, said dogs being of different effective magnitudes so as to alternately engage said escapement wheel, and a spring for normally holding said dogs for engagement with said wheel.
19. In a computing machine, a state controller comprising a disk having a series of openings therein, and a series of buttons eccentrically mounted in said openings.
20. In a computing machine, a state controller comprising a disk having a series of openings therein, and a series of state-determining buttons adjustably mounted in said openings, so as to vary their effective location with respect to each other and with respect to said disk.
21. In a computing machine, a state controller comprising a disk having a series of perforations therein, and a series of state-determining buttons projecting effectively some on one side of said disk and some on the other side of said disk.
22. In a computing machine, a state controller comprising a disk having a series of openings therein, and a series of eccentrically headed state-determining buttons mounted in said openings.
23. In a computing machine, a state con-

troller comprising a disk having a series of openings therein, and a series of eccentrically headed position-determining buttons mounted in said openings, said buttons being 5 rotatable in said openings to vary their radial position with respect to said disk and thus vary their effect.

24. In a computing machine, a state controller comprising a disk having a series of 10 openings therein, a series of eccentrically headed state-determining buttons mounted in said openings, said buttons being rotatable in said openings to vary their radial position with respect to said disk and thus 15 vary their effect, and means for locking said buttons in any adjusted state-determining position.

25. In a computing machine, a state controller comprising a disk having a series of 20 perforations therein, and a series of state-determining buttons secured at said perforations, said state-determining buttons each including a head, a shank eccentrically located on said head and extending through 25 one of said openings and a nut engaging said shank to lock said button in position on said disk.

26. The combination with a computing 30 mechanism, of a controller for governing the state of said computing mechanism, a shifter engaging said controller, a linkage connecting said shifter with said computing mechanism, whereby said controller can operate through said shifter and said linkage 35 to govern the state of said computing mechanism, said shifter being composed of separable movable parts so as to enable the interruption of the control by said controller of said computing mechanism.

40. 27. The combination with a computing mechanism, of a controller for governing the state of said computing mechanism, a shifter engaging said controller, a linkage connecting said shifter with said computing mechanism, whereby said controller can operate through said shifter and said linkage 45 to govern the state of said computing mechanism, said shifter being composed of separable movable parts so as to enable the interruption of the control by said controller of said computing mechanism, said linkage including a hand lever capable of assuming control irrespective of the state determined by said controller.

50. 28. The combination with a computing mechanism, of a controller for governing the state of said computing mechanism, a shifter engaging said controller, and a linkage connecting said shifter with said computing mechanism to enable the control of said computing mechanism by said controller, said shifter being composite to enable the interruption of the connection between said controller and said computing mechanism and 55 comprising a bell crank having two arms, an

arm mating with one of said arms and a latch for securing the two mating arms detachably together.

29. The combination with a computing mechanism, of a controller for governing 70 the state of said computing mechanism, a shifter actuated by said controller, and a linkage connecting said shifter to said computing mechanism, said shifter being composite and comprising a bell crank lever 75 having a plurality of arms, a pivotally mounted arm mating with one of said first-mentioned arms, and a spring latch for connecting said mating arms together.

30. The combination with a computing 80 mechanism, of a controller for governing the state of said computing mechanism, a shifter actuated by said controller, and a linkage connecting said shifter to said computing mechanism, said shifter being composite 85 and comprising a bell crank lever having a plurality of arms, a pivotally mounted arm mating with one of said first-mentioned arms and a spring latch for connecting said mating arms together, said linkage including a hand lever adapted to assume 90 manual control and give a condition to said computing mechanism other than that determined by said controller, said latch yielding on an actuation of said hand lever to 95 enable the divorcing of said mated arms and the freeing of said computing mechanism from subservience to said controller.

31. The combination with a computing 100 mechanism, of a controller for governing the state of said computing mechanism, a shifter operated by said controller, and a linkage connecting said shifter with said computing mechanism, said shifter being composite and including mating parts separable from each 105 other to free said computing mechanism from subservience to said controller.

32. The combination with a computing 110 mechanism, of a controller for governing the state of said computing mechanism, a shifter actuated by said controller, a linkage connecting said shifter with said computing mechanism, said shifter being composite and comprising a pivotally-mounted bell crank having a plurality of arms, one of said arms 115 having a V-groove therein, a separate arm mating with one of said first-mentioned arms, and a latch pivotally mounted on the separate mating arm and detachably engaging said V-groove.

120. 33. The combination with a computing mechanism, of a controller for governing the state of said computing mechanism, a shifter actuated by said controller, a linkage connecting said shifter with said computing mechanism, said shifter being composite and comprising a pivotally-mounted bell crank having a plurality of arms, one of said arms having a V-groove therein, a separate arm mating with one of said first-mentioned 125 arms.

- arms, and a latch pivotally mounted on the separate mating arm and detachably engaging said V-groove, said linkage being connected to said separate arm and including a 5 hand lever capable of manipulating said separate arm by forcibly disengaging said latch so as to control the state of said computing mechanism independent of said controller.
- 10 34. The combination with a computing mechanism, of an automatic mechanism for controlling the state of said computing mechanism, a yielding connection between said automatic mechanism and said computing mechanism, and manual means for affording a state other than that determined by said automatic mechanism by temporarily forcibly disrupting said yielding connection between said automatic mechanism and said 15 computing mechanism, said connection between said automatic mechanism and said computing mechanism automatically re-completing itself when said manual means adjusts said computing mechanism to a state 20 accordant with that determined by said automatic mechanism.
35. The combination with a plurality of computing heads, of a controller disk for governing the state of said computing heads, and a plurality of shifters, one for each of 30 said computing heads coöperating with opposite sides of said disk to enable the control of the state of all said computing heads by said disk.
- 35 36. The combination with a plurality of computing heads, of a controller for governing the state of said computing heads, said controller having a plurality of position-determining members thereon projecting from 40 opposite sides thereof, and a plurality of shifters one for each of said computing heads connected to said computing heads and engaging the position-determining members on opposite sides of said controller.
- 45 37. The combination with a computing mechanism, of an automatic controlling mechanism for governing the state of said computing mechanism, and automatic means coming into play for limiting the effectiveness of said automatic mechanism.
- 50 38. The combination with a computing mechanism, of a state-controlling mechanism for governing the action of said computing mechanism, and a lock for preventing the action of said state-controlling mechanism beyond a predetermined limit.
- 55 39. The combination with a computing mechanism, of a state-controlling mechanism for governing the action of said computing mechanism, and means for preventing the action of said state-controlling mechanism beyond a predetermined limit, said means being adjustable to vary the limit 60 of action of said state-controlling mechanism. 65
40. The combination with a computing mechanism, of a state-controlling mechanism for governing the character of computation carried on by said computing mechanism, and means for limiting the effectiveness of said state-controlling mechanism to any point between a minimum and a maximum extent of control. 70
41. The combination with a computing mechanism, of a typewriting mechanism including a carriage, a state-controlling mechanism for governing the character of computation carried on by said computing mechanism, and a lock for preventing a certain movement of said carriage when said state-controlling mechanism has reached the 80 limit of its action. 75
42. The combination with a computing mechanism, of a typewriting mechanism including a carriage, a state-controlling mechanism for governing the character of computation carried on by said computing mechanism, a lock for preventing a certain movement of said carriage when said state-controlling mechanism has reached the 90 limit of its action, and means for varying the position of said lock to vary the limit of action of said state-controlling mechanism. 85
43. The combination with a computing mechanism, of a typewriting mechanism including a traveling carriage, means to control the movements thereof, an automatic mechanism for controlling the state of said computing mechanism, and means to control 100 said automatic mechanism to move automatically to correspond with the traveling movement of said carriage. 95
44. The combination with computing mechanism, of a typewriting mechanism including a traveling carriage, an automatic mechanism for controlling the state of said computing mechanism, means for controlling the movements of said carriage and said automatic mechanism so that the movements 110 of said automatic mechanism correspond with the traveling movements of said carriage, and means to prevent a relative movement of said carriage by said controlling means after said automatic mechanism has 115 reached the limit of its effectiveness. 105
45. The combination with computing mechanism, of a typewriting mechanism including a traveling carriage, an automatic mechanism for controlling the state of said computing mechanism, means for controlling the movements of said carriage and said automatic mechanism so that the movements 120 of said automatic mechanism correspond with the traveling movements of said carriage, and means to prevent a relative movement 125 of said carriage by said controlling means after said automatic mechanism has reached

the limit of its effectiveness, said preventing means being adjustable to vary the limit of effectiveness of said automatic mechanism to correspond with the number of computing zones or columns as determined by said carriage.

46. The combination with a computing mechanism, of a state-controlling mechanism for governing the character of action 10 of said computing mechanism, an escapement for said state-controlling mechanism, and a lock for preventing a further actuation of said escapement when said state-controlling mechanism has reached the limit of 15 its action.

47. The combination with a typewriting mechanism including a carriage and a tabulating mechanism for governing the movement of said carriage, of a computing mechanism, an automatic mechanism for governing the action of said computing mechanism, and a lock for said tabulating mechanism actuated by said automatic mechanism.

48. The combination with a typewriting mechanism including a carriage and a tabulating mechanism for determining the position of said carriage, of a computing mechanism, and an automatic mechanism for determining the state of said computing mechanism, and means for concomitantly locking said tabulating mechanism and said automatic mechanism against actuation.

49. The combination with a typewriting mechanism including a carriage and a tabulating mechanism for determining the position of said carriage, of a computing mechanism, an automatic mechanism for determining the state of said computing mechanism, and means for concomitantly locking said tabulating mechanism and said automatic mechanism against actuation, said locking means being adjustable to vary the instant of locking.

50. The combination with a computing mechanism, of a controlling mechanism for governing the state of said computing mechanism, said controlling mechanism including a rotatable disk and a lock for preventing the further rotation of said disk after 50 said disk has rotated a predetermined amount.

51. The combination with a typewriting mechanism including a traveling carriage with an escapement for said carriage, of a computing mechanism, an automatic mechanism for controlling the state of said computing mechanism, an escapement for said automatic mechanism, means for concomitantly actuating both of said escapements, 60 and a lock for preventing a certain action of both said escapements after said second-mentioned escapement has enabled a predetermined movement of said controlling mechanism.

65 52. The combination with computing

mechanism, of state-controlling mechanism therefor, and means to prevent further movement of said state-controlling mechanism after said mechanism has reached a predetermined limit, said means including 70 a disk, an escapement wheel connected to said disk and having teeth thereon, a dog engaging individually with said teeth to prevent rotation of said wheel and moving away from said teeth to enable the rotation 75 of said wheel and thereby of said disk, to govern the different positions of said state-controlling mechanism, and a guard located in juxtaposition to one of said teeth to prevent the disengagement of said dog from 80 said last-mentioned tooth.

53. The combination with computing mechanism, of state-controlling mechanism therefor, and means to prevent further movement of said state-controlling mechanism after said mechanism has reached a predetermined limit, said means including 85 a disk, an escapement wheel connected to said disk and having teeth thereon, a dog engaging individually with said teeth to prevent rotation of said wheel and moving away from said teeth to enable the rotation 90 of said wheel and thereby of said disk to govern the different positions of said state-controlling mechanism, and a guard located 95 in juxtaposition to one of said teeth to prevent the disengagement of said dog from said last-mentioned tooth, said guard being adjustable to coöperate with any one of the teeth on said escapement wheel, so as to 100 vary the point at which the movement of said state-controlling mechanism is prevented.

54. The combination with computing mechanism, of a carriage traveling to determine different computing zones of said computing mechanism, driving means for traversing said carriage, state-controlling mechanism for determining the character of computations carried on by said computing 105 mechanism, driving means for said state-controlling mechanism, and a tabulating mechanism including a set of tabulator keys connected to control the action of both said driving means.

55. The combination with a plurality of computing heads, of a state-controlling mechanism for governing the action and character of action of said computing heads, said state-controlling mechanism including 110 a double faced member having parts on one face to control the states of one of said computing heads according to a predetermined plan, and parts on the other face to control the states of another computing head according to a predetermined plan.

56. The combination with computing mechanism, of automatic state-controlling mechanism for giving a predetermined set of states for said computing mechanism, con- 130

- nections joining said automatic state-controlling mechanism to said computing mechanism, so that said automatic state-controlling mechanism will normally control said computing mechanism, and manual means in said connections comprising a latch forcibly moved out of position by said manual means, parts of said automatic state-controlling mechanism acting as a resistance but enabling said latch to be so moved to break said connections to enable said manual means to control states of said computing mechanism different from those determined by said automatic state-controlling mechanism. 5
57. The combination with computing mechanism, of automatic state-controlling mechanism for giving a predetermined set of states for said computing mechanism, yielding connections generally joining said automatic state-controlling mechanism to said computing mechanism, so that said automatic state-controlling mechanism will be normally in ascendancy over said computing mechanism, and manual means for forcibly usurping the control of the state of said computing mechanism from said automatic state-controlling mechanism by concomitantly manipulating parts of said computing mechanism and breaking said yielding connections, thereby obtaining states of said computing mechanism different from those determined by said automatic state-controlling mechanism, the state of said computing mechanism automatically coming into step with the state determined by said state-controlling mechanism when said connections are re-completed at the abdicating of the manual controlling means. 20
58. The combination with a computing mechanism, of two primary elements for said computing mechanism, to wit, a carriage traveling to determine different computing zones of said computing mechanism and a state-controlling mechanism acting to determine the computation and character of computation of said computing mechanism, returning means for each of said primary elements to bring them back to an initial starting point after a series of movements, and a lock for insuring the return of both said primary elements by their respective returning means. 25
59. The combination with a computing mechanism, of a traveling carriage, means controlling said carriage so as to give it repeated movements for determining different computing zones, state-controlling mechanism for said computing mechanism, means controlling said state-controlling mechanism so as to give it repeated movements for determining desired states for different computing zones, the movements of said carriage and said state-controlling mechanism being each free and untrammelled by the move- 30
- ments of the other, and key-controlled means for controlling said carriage-controlling means and said state-controlling means to cause said repeated movements of both said carriage and said state-controlling mechanism to correspond zone for zone. 70
60. The combination with a computing mechanism, of a carriage traveling to determine computing zones of said computing mechanism, state-controlling mechanism acting to determine the computing action and character of computing action of said computing mechanism for each zone as determined by said carriage, said carriage and said state-controlling mechanism having independent drives, and a single set of keys having ascendancy over both of said drives, so that said drives will act at the same time independently and in unison. 75
61. The combination with one or more computing heads, of manual controlling means for determining the state of said computing heads so as to determine the computation and character of computation carried on by said computing heads, automatic controlling means for governing the state of said computing heads, and connections common to both said automatic and said manual controlling means, said connections giving way when forced by said manual means so that said automatic controlling means loses dominance over said computing heads when the manual means is actuated to change the state of said computing heads. 80
62. The combination with a traveling carriage, of one or more computing heads, a controlling mechanism for governing the state of said computing heads according to a predetermined plan or sequence, and to accord with the position of said carriage, said controlling mechanism including a rotatable disk, tabulating mechanism, and means, independent of the position of said carriage, brought into action by said tabulating mechanism for controlling the rotation of said disk. 100
63. The combination with a computing mechanism, of typewriting mechanism having a carriage traveling to determine different computing zones for said computing mechanism, said carriage having both interzonal and intrazonal movements, said typewriting mechanism having tabulating mechanism for determining the interzonal movements of said carriage, automatic state-controlling mechanism for giving a predetermined series of states of said computing mechanism, and driving means for said state-controlling mechanism dominated by said tabulating mechanism to give actions of said state-controlling mechanism concordant with interzonal movements of said carriage. 105
64. The combination with computing mechanism, of an automatic state-control- 110

ling mechanism for governing the action of said computing mechanism according to a predetermined plan, said state-controlling mechanism having a variable capacity with 5 different numbers of zones to a cycle of computing operations, and an adjustable lock for determining the capacity of said state-controlling mechanism and thus the number of zones in a cycle of computing 10 operations.

65. The combination with a computing mechanism, of an automatic state-controlling mechanism for said computing mechanism arranged to give a predetermined series of states of said computing mechanism, 15 actuating means dominating said state-controlling mechanism and giving an action of the latter at each operation of the former, and a lock for preventing an action of said

actuating means after a number of successive operations of said automatic state-controlling mechanism.

66. The combination with typewriting mechanism including a traveling carriage and an escapement therefor, of a computing 25 mechanism, automatic mechanism for determining the state of said computing mechanism to accord with different typewriter columns as written by said typewriting mechanism, tabulator keys for said carriage, an 30 escapement for said automatic mechanism, and means controlled from said tabulator keys for operating said escapement.

GUSTAVE O. DEGENER.
